[57] CLAIM

The ornamental design for a hand-held portable medical monitor for managing the administration of medication and medical treatment regimens, as shown and described.

DESCRIPTION

FIG. 1 is a top perspective view of a hand-held portable medical monitor for managing the administration of medication and medical treatment regimens, with its top cover in a closed position, showing our new design;

FIG. 2 is a top plan view a hand-held portable medical monitor for managing the administration of medication and medical treatment regimens thereof;

FIG. 3 is a bottom plan view a hand-held portable medical monitor for managing the administration of medication and medical treatment regimens thereof;

FIG. 4 is a front elevational view a hand-held portable medical monitor for managing the administration of medication and medical treatment regimens thereof;

FIG. 5 is a rear elevational view a hand-held portable medical monitor for managing the administration of medication and medical treatment regimens thereof;

FIG. 6 is a left side elevational view a hand-held portable medical monitor for managing the administration of medication and medical treatment regimens thereof;

FIG. 7 is a right side elevational view a hand-held portable medical monitor for managing the administration of medication and medical treatment regimens thereof; and,

FIG. 8 is a top perspective view on a reduced scale thereof, with its top cover in an open position and its five compartment lids in closed position.

The broken line showing in FIGS. 3, 5 and 7 is for illustrative purposes only and forms no part of the claimed design.
